JOHN C. F. RISHEL AND LEANDER K. RISHEL, OF DANVILLE, PENN.
SYLVANIA.

RAILWAY-TORPEDO PLACER.

SPECIFICATION forming part of Letters Patent No. 366,029, dated July 5, 1887.

Application filed May 9, 1885. Serial No. 164,983. (No model.)

To all whom it may concern:

Be it known that we, JOHN C. F. RISHEL and LEANDER K. RISHEL, citizens of the United States, residing at Danville, in the 5 county of Montour and State of Pennsylvania, have invented a new and useful Improvement in Railroad-Torpedo Attachers, of which the following is a description.

This invention relates to that class of torpedo which are used upon railroad-rails to be exploded by a passing train to give a signal to the engineer; and it has for its object to attach a torpedo to a rail from the rear end of a moving train without stopping or slackening 15 the speed of the train for that purpose.

To this end our invention consists in a certain device for attaching a torpedo to a rail and in an implement for applying the same, constructed and operated as hereinafter described and claimed, reference being had to the accompanying drawings, in which—

Figure 1 is a front elevation of our invention. Fig. 2 is a central vertical section of the same, and Fig. 3 is a transverse vertical 25 section of a railroad-rail with our torpedo attached to it as in use.

A represents a railroad-rail.

B is a torpedo of any usual form. Such torpedoes are usually in boxes like blacking-boxes, about two inches across and one-quarter of an inch thick, containing powder, which is exploded by the crushing effect of a wheel passing over it when attached to the top of a rail. This attaching is usually done by means 35 of a strip of lead, corresponding in form and position to the spring C, and it is done by first stopping the train from which the signal is to be set. Then a person gets off the train and places the torpedo on a rail behind the 40 train and pinches the lead strip under the cheeks of the rail to keep the torpedo from being jarred off. When not in use, the lead strip is folded backward around the torpedo. As now used, the softness and pliability of 45 lead is a necessity, in order that it may be used as described.

In place of the pliable lead strip we provide a spring, C, of steel or other suitable material, set in shape, as shown in Fig. 3. The ends D of the spring naturally spring toward the rail.

To apply the torpedo, a suitable implement

or holder is necessary, and we have devised the following: E is a hollow shank or socket adapted to fit upon a handle, F, and provided with a fork, G, having hooks H at the end, in which hooks the ends of the spring C may be placed by spreading the ends of the spring apart. J is a presser, shaped to rest upon the torpedo and provided with a shank, K, entering into the socket E, to be acted upon by a spring, L, which pushes the presser outward. M is a shoulder on the shank K, to receive the action of spring L and to prevent the shank from being pushed entirely out of the socket. The spring of the torpedo pushes upward 65 when its ends are separated, and the presser J is provided with the spring L, to hold the torpedo in the fork and hooks.

We usually apply a torpedo-holder on each end of the handle, which is long enough to reach the rail with by an operator on the car-platform. Having fixed the torpedo in the holder, the operator, standing on the rear platform of a train, guides the fork to straddle the rail, then making a quick but light thrust downward the torpedo strikes the rail, pushing back the presser-spring and raising the ends of spring C out from the retaining-hooks H, leaving the spring C to grasp the head of the rail, whereby the torpedo is held in place 80 on the rail, to be exploded by a following train. Should the signal agreed upon require two torpedoes to be set near together, the holder will be reversed, and the torpedo in its opposite end will be set in the manner described. 85

While this holder might be used successfully when made as described, yet I prefer to provide a cushion, Q, consisting of rubber or other springy substance, against which the presser J may abut if the operator chances to 90 strike the torpedo down too hard upon the rail, in order that all possibility of accidental explosion may be avoided. The spring offers a yielding resistance proportional to the strength of the torpedo-case, so that the latter cannot be dangerously struck when in the holder.

What we claim as our invention, and desire to secure by Letters Patent, is—

1. The torpedo-placer, consisting of a staff 100 having a chambered ferrule with branched and notched arms in its lower end, in combi-

nation with a rectilinearly moving plunger arranged within said ferrule and provided with a spiral spring and stop for limiting the outward movement of the plunger, substantially as described.

2. The combination of a torpedo, a spring, substantially as described, attached thereto, a forked holder provided with hooks within the fork, a spring-presser adapted to hold the torpedo in conjunction with the said hooks, and an abutting cushion behind the presser, sub-

stantially as shown and described, for the purpose specified.

The above specification of our invention signed by us in the presence of two subscribing witnesses.

JOHN C. F. RISHEL.
LEANDER K. RISHEL.
